UNITED STATES PATENT OFFICE.

LEWIS C. SMITH, OF PORT JEFFERSON, OHIO, ASSIGNOR TO HIMSELF AND
THOMPSON G. DICKERSON, OF SAME PLACE.

DESIGN FOR A GRAVE-COVER.

SPECIFICATION forming part of Design No. 20,992, dated August 18, 1891.

Application filed July 9, 1891. Serial No. 398,972. Term of patent 14 years.

To all whom it may concern:

Be it known that I, LEWIS C. SMITH, a citizen of the United States, residing at Port Jefferson, in the county of Shelby and State 5 of Ohio, have invented and produced a new and original Design for Grave-Covers, of which the following is a specification.

Reference is to be had to the accompanying drawing, forming a part of this specification, in which the figure represents in perspective a grave-cover embodying my new design.

The design consists in the ornamentation and configuration shown.

15 The body A of the cover at the longitudinal sides and the foot has vertical corrugations a, which give to the top a' a scalloped appearance at its outer edges. At the base or lower edge of the body A the lines of the 20 flange B depart outwardly, the flange having a scalloped edge, as at b. The lines of the top a' depart inwardly a short distance and ter-

minate in the vertical ornamental flange a², the said flange being in the form of oppositely-disposed double-ogee corners and having a scalloped edge. The surface of the top a' is ornamented at the head and foot, as at C D, that at the head consisting of the figures of angels bearing a wreath. At the foot is a figure D, comprising a transversely-ranging member d, from which the ends d' depart at about right angles, the defining edges of the figure being in short curves, approaching a scalloped effect. Rising from the body A, at the head, is the arch E, from the sides of which the arms or branches e depart in compound curves.

I claim—

The design for a grave-cover herein shown and described.

LEWIS C. SMITH.
